COMBINED ASH TRAY, CIGARETTE HOLDER, AND LIGHTER

Solomon Adler, Kew Gardens, N. Y.

Application October 12, 1950, Serial No. 12,538

Term of patent 7 years

(Cl. D85—2)

To all whom it may concern:

Be it known that I, Solomon Adler, a citizen of the United States of America, residing in Kew Gardens, county of Queens, State of New York, have invented a new, original, and ornamental Design for a Combined Ash Tray, Cigarette Holder, and Lighter, of which the following is a specification, reference being had to the accompanying drawings, forming a part thereof, wherein:

Fig. 1 is a top plan view of a combined ash tray,

cigarette holder and lighter showing my new design;

Fig. 2 is an end elevational view thereof; and
Fig. 3 is a side elevational view of the same.

I claim:

The ornamental design for a combined ash tray, cigarette holder, and lighter, substantially as shown.

SOLOMON ADLER.
